(57) **CLAIM**

The ornamental design for a fishing rod holder, as shown and described.

DESCRIPTION

FIG. 1 is a front, top, and left side perspective view of a fishing rod holder in an open position showing my new design;

FIG. 2 is a left side elevation view thereof;

FIG. 3 is a right side elevation view thereof;

FIG. 4 is a rear elevation view thereof;

FIG. 5 is a front elevation view thereof;

FIG. 6 is a top plan view thereof;

FIG. 7 is a bottom plan view thereof;

FIG. 8 is a front, top, and left side perspective view thereof in a closed position;

FIG. 9 is a front, top, and left side perspective view thereof showing attachment to a post and attachment of a fishing rod, and,

FIG. 10 is a front, top, and left side perspective view thereof showing partial assembly.

The broken lines showing a post and a fishing rod in FIG. 9 are for illustration purposes and form no part of the claimed design.
